(57) **CLAIM**

The ornamental design for a slab comprising particulate mineral material, as shown and described.

DESCRIPTION

The file of this patent contains at least one drawing/photograph executed in color. Copies of this patent with color drawing(s)/photograph(s) will be provided by the Office upon request.

The sole FIGURE is a top plan view of a slab comprising particulate mineral material, showing our new design. The depicted surface of the slab is flat. The broken lines represent portions of the slab that form no part of the claimed design.
